CLAIM

The ornamental design for a display screen with a graphical user interface for a security system, as shown and described.

DESCRIPTION

FIG. 1 is a front view of a display screen with a graphical user interface for a security system showing my new design; and,

FIG. 2 is a second embodiment thereof.

The broken lines showing a display screen and elements of the graphical user interface illustrate portions of the article, and form no part of the claimed design.

1 Claim, 2 Drawing Sheets

FIG. 1

FIG. 2
